BOOKBINDING MACHINE

Robert B. M. Taylor, Newark, N. J., assignor, by
mesne assignments, to Paralex Corporation,
Newark, N. J., a corporation of New Jersey

Application March 25, 1936, Serial No. 70,743

16 Claims. (Cl. 11—1)

The invention relates to book binding machines, and more particularly to a machine adapted for use in the binding of books in which the collated sheets are bound by means of a coiled wire passing through registering openings in the various leaves.

Prior to my invention, there has been extensively used a binding for notebooks and similar articles consisting of a spirally wound wire 10 threaded through a sequence of registering openings in the several leaves of the book. This type of book has the objectionable feature that each leaf of the book, as it is turned, has a component of movement axially of the spiral binding wire, 15 the amount of this movement varying with the pitch of the convolutions of the wire. Since the series of openings through each leaf are closely adjacent the edge of the leaf, there is likelihood of tearing of the leaves during their turning movement.

Books bound by means of coiled wire ordinarily require the turning of the leaves of no more than 180°, but even with this quantity of arcuate or turning movement there is likelihood of tearing of the leaves. Furthermore, there is a varying degree of axial movement as the number of turned leaves increases.

I have, prior to my present invention, devised a wire bound book in which substantially 180° of each convolution of a coiled wire occupies a plane at right angles to the axis of the coil, and in which such portion of each convolution positioned beyond the edge of the book is connected with the adjacent convolution by a section of wire extending obliquely to said axis.

The machine of the present application is so constructed as to produce a binding of the type immediately above referred to, by distorting each convolution of a spirally wound binder wire to 40 give the desired obliquity to substantially 180° in arc of each convolution, and to bring the remaining 180° of each convolution into a plane at right angles, or perpendicular, to the axis of the binder wire.

In a machine embodying the invention, I provide a sequence of presser bars, so spaced in relation to each other and to a feed table as to permit the rapid feeding of books previously bound by means of a spiral binding wire, with each convolution of the wire engaging one of the presser bars, the construction being such that, irrespective of accuracy in the position of the books being fed, the binder wire will automatically find a proper position in relation to said presser bars.

The arrangement and number of presser bars

may be such as to permit the machine to operate simultaneously upon a plurality of books, thus increasing the production of the machine by the completion of the binding of a plurality of books upon each cycle of operations of the machine.

When power is applied to the machine, the presser bars are actuated to increase the angularity or obliquity of the portion of each convolution of the binder wire positioned beyond the edge of the book to an extent to bring the remaining portion of each convolution throughout substantially 180° in arc into an approximately true circular form, positioned in a plane at right angles, or perpendicular, to the axis of the binder wire.

In order to secure the desired mode of operation of the machine, it is essential to provide means preventing movement of the book or books being bound while the presser bars are being actuated to distort, deform or warp the convolutions of the wire. In the machine of the invention, the books are held by a clamp bar which is automatically engaged with the books being bound following the initial application of power to the presser bars. Preferably, the clamp bar is engaged with the books by spring pressure, thus limiting the action of the bar to a light clamping action, merely sufficient to hold the books against movement with the presser bars and without in any way deforming the book adjacent the binder wire. It is preferable to control the clamp mechanism through the presser bar actuating mechanism so as to ensure accuracy in the timing of the parts of the machine, and to so construct this clamp mechanism that its operating effect may be modified so as to adapt the machine to different thicknesses of books.

In conjunction with the clamping mechanism and the presser bar mechanism, I provide a feed table having a gauge bar adjacent the presser bars and so spaced therefrom as to permit the descent of a portion of each convolution of the binder wire below the plane of the table, thus permitting the book or books to lie flat upon the table and the edge of the leaves to squarely abut the presser bars.

In addition to the foregoing characteristics, a machine embodying the invention may be so adjusted as to adapt it to use in binding books in which the binder wires have a different pitch angle and to permit the control of the extent of distortion of each convolution of said wire to secure the desired form of that portion of each convolution upon which the leaves run during the turning thereof.

While a machine embodying the invention may be operated by hand, if desired, I preferably provide a manually controlled, intermittently operative actuating mechanism for applying power to the machine.

The gauge plate of the machine is also preferably capable of adjustment toward and from the presser bars to accommodate the machine to use with binder wires, the convolutions of which have different diameters.

The invention consists primarily in a book binding machine embodying therein a feed shelf, a rack having a plurality of spaced presser bars positioned in a plane perpendicular to the plane of said feed shelf, actuating means for said rack whereby said presser bars are moved in relation to said feed shelf while engaging the convolutions of a binding wire of a book upon said feed shelf, to increase the obliquity of the portion of each such convolution projecting beyond the edge of the book, and means resisting movement of the book with said presser bars; and in such other novel features of construction and combination of parts as are hereinafter set forth and described, and more particularly pointed out in the claims hereto appended.

Referring to the drawing,

Fig. 1 is a longitudinally condensed front elevation of a machine embodying the invention with parts broken away, and indicating in dotted lines different positions of the rack actuating mechanism;

Fig. 2 is a section on the line 2—2 of Fig. 1;

Fig. 3 is a plan view of a portion of the machine at the left of Fig. 1;

Fig. 4 is an enlarged detail view of a fragmentary portion of a book showing the position of the presser bars in relation to the convolutions of the binder wire, before the actuation of the machine; and

Fig. 5 is a similar view showing the relation of parts upon the completion of the actuation of the machine.

Like numerals refer to like parts throughout the several views.

In the embodiment of the invention shown in the drawing, the main table of the machine is shown at 10 and the feed shelf carried thereby at 11. At one side of the feed shelf 11 is a rack 50 which, in the form of the invention shown, comprises a fixed lower bar 12 and an upper bar 13 supported from the lower bar by means of links 14 and 15 pivotally connected with said bars so as to permit relative movement of the bars in the same vertical plane. Extending between the bars 12 and 13 are presser bars 16, these presser bars being spaced apart a distance sufficient to receive a portion of a binder wire therebetween.

Each presser bar preferably consists of a straight portion projecting substantially perpendicularly to the plane of the feed shelf 11 and means pivotally connecting the opposite ends thereof with said rack bars 12 and 13 respectively so as to permit relative movement of said rack bars and cause the tilting of said presser bars. As shown in the accompanying drawing, this pivotal connection between the presser bars and the rack bars is by means of ends 17 and 18 upon each bar extending at right angles to the portion of the bar extending between the rack bars, these ends being seated in bearing sockets in the rack bars respectively. The presser bars are held in relation to the rack bars in the form of the invention shown by means of cap plates 19

and 20 carried by the rack bars respectively and engaging the portion of the presser bars adjacent the ends thereof. These cap plates are connected with the rack bars by means of screws to permit the removal and the substitution of presser bars in effecting repairs to the machine, as well as to facilitate assembling the presser bars in the machine.

In the form of the invention shown, the lower rack bar 12 is secured to a back frame 21 by means of screw bolts 22 so as to hold the rack bar 12 against movement while the rack bar 13 is receiving a parallel movement by the actuating means therefor.

Mounted adjacent one end of the machine is a wheel 23 carrying a crank 24 adjustable radially of said wheel so as to permit the adjustment of the actuating mechanism for the presser bars 16 in a manner to control the extent of the tilting of these bars with each actuation of the machine.

Pivotedly connected with the crank 24 and with the link 14 is a pitman 25, the radial distance of the pivotal connection between this pitman and said link being such as to impart a desired throw to the link 14 and a required parallel movement to the rack bar 13. The point of application of power from the pitman 25 to the link 14 is immaterial to the invention and may be varied in different machines, particularly as the throw of the link 14 and the quantity of tilting movement of the various presser bars 16 may be controlled by adjustment of the crank 24 radially of the wheel 23.

In the accompanying drawing, the actuating mechanism for the presser bars, including the crank wheel 23, is power driven through the medium of a driving pulley 26 idly mounted upon the shaft of the wheel 23 and adapted to be connected therewith by means of an ordinary clutch mechanism 27 which may be controlled through a link 28 connected with a control pedal (not shown). This clutch mechanism 27 corresponds with the clutch of an ordinary power driven punch press, and a detailed description thereof is therefore unnecessary, beyond to state that the use of such a clutch mechanism results in an intermittently operative machine, the actuation of which is manually controlled so as to afford time for the feeding of work to the machine.

The edge of the feed shelf 11 is spaced from the various presser bars 16 and said shelf has adjustably mounted thereon a gauge plate 29 movable toward and from the presser bars for the purpose of permitting the machine to be used in the final binding operation upon books, the leaves of which are connected by binder wires, the convolutions of which have different diameters. The gauge plate 29 is always spaced from the presser bars 16, but the distance between the edge of this plate and said bars is determined by the diameter of each convolution of the binder wire. The purpose of the plate is to permit the collated leaves of a book to lie flat upon the feed shelf 11 and the gauge plate 29, with the portions of the binder wire projecting from the bottom-most leaf and across the back of the collated leaves extending beyond the edge of the gauge plate. By having the collated leaves lie perfectly flat upon the feed shelf, it is possible to bring the edge of the book adjacent the binder wire in abutting relation to the presser bars, which is desirable as maintaining the proper position of the leaves and of the binder wire in relation to each other and to said presser bars.

As will more fully appear hereinafter, in feeding books to the presser bar mechanism, it is merely necessary to push these books toward the presser bars, the rounded contour of which, by engagement with the rounded presser bars, will impart such movement to the book as may be found necessary to cause engagement of a presser bar with each convolution of the binder wire.

Upon the operation of the machine, however, the thrust of the presser bars against all of the convolutions of the binder wire of each book will tend to impart movement to the book longitudinally of the binder wire. To prevent this shifting of the book, I provide a clamp bar 30 which, with each actuation of the machine, will be forced downwardly into a light pressure engaging relation with the book or books upon the feed shelf so as to develop a light clamping action adjacent the binder wire.

The clamp bar 30 is supported from cranks 31 of a crank shaft 32 by means of arms 33 and 34 rigidly secured to said crank arms 31. Acting upon the crank shaft 32 are torsion springs 35 and 36 for imparting movement to said shaft and to the crank arms 31 and limiting the amount of pressure applied through the clamp bar 30 to the book or books.

Carried by the shaft 32 is a crank arm 37 having adjustably mounted therein a bearing member 38 carrying a roller 39 bearing upon the rack bar 17. By this construction, the movements of the clamp bar 30 are accurately timed in relation to the presser bars 16 with a progressively increasing pressure as the presser bars 16 approach the limit of their movement or the greatest extent of their tilting action.

In the accompanying drawing, the collated leaves are shown at 40 and the convolutions of the binder wire at 41.

The adjustment of the gauge plate is secured by means of a slot and set screw connection 42 between the feed shelf 11 and said gauge plate, or in any other desired manner.

The operation of the herein described machine is substantially as follows:—

In books bound by means of a spirally wound wire, the collated leaves have a spiral trend, or a trend axially of the binder wire. This trend will be to the left of Fig. 4. In the operation of the machine of the invention, this trend is corrected, so that the various leaves of a book, when completely bound, will have the edges of all leaves trued up in relation to each other.

While a half hard wire may be used in binding the leaves of a book, which wire may be readily distorted, deformed or warped by the rapid application of pressure thereto from the presser bars 16, there will always be a reflex of the material of the wire so as to necessitate an overthrow of the presser bars to ensure a proper form of each convolution of the binder wire, notwithstanding the reflex action above referred to.

In the operation of the machine, a book bound with an ordinary spirally wound wire is placed upon the feed shelf 11 and advanced by hand across the gauge plate 29 until the edge of the leaves engage the binder wire above the presser bars 16. The gauge plate 29, before beginning a run of the machine, is so set as to permit a portion of each convolution of the binder wire to pass the edge, and drop below the plane of, the gauge plate, so as to permit the leaves to lie perfectly flat upon the feed shelf, and the gauge plate when the edge of the leaves is in abutting relation to the presser bars. No particular care need be taken

in feeding the books, since the engagement of the binder wire with the rounded contour of the presser bars will automatically shift the book so as to accurately position each convolution of the binder wire between two adjacent presser bars. 5 The pitch of the wire will assist in thus positioning the book.

When one or more books have been positioned with the binder wire thereof in the operative relation to presser bars 16, the clutch mechanism 27 10 is actuated to apply power from the pulley 26 to the crank wheel 23, thus actuating the crank 24 and, through the pitman 25, oscillating the link 14 and causing a similar oscillation of the link 15 through the upper rack bar 13. Since the lower 15 rack bar 12 is stationary, this will cause a parallel movement of the rack bar 13, causing a tilting of the various presser bars. During this tilting movement, the rack bar 13 descends and the ends of the various presser bars have pivotal movement 20 in relation thereto and to the rack bar 12.

With the turning of the crank wheel 23, the crank of which, when the machine is at rest, is at a horizontal center of said machine, the quantity of movement of the link 14 during the early 25 stages of the movement of the crank wheel will be small, but the quantity of movement will increase as the crank approaches and passes beyond the vertical center of the crank wheel. During the final portion of 180° of movement of the 30 crank wheel, the movement of the link 14 and the various presser bars will gradually become slower until the crank is upon the opposite horizontal center, and the initial return movement will be slow with a gradual increase in this movement, followed by a lowering of the speed thereof until the machine comes to rest upon the completion of the cycle. The speed of the crank wheel may be as high as 300 R. P. M., and the slowing down of the movement of the presser bars, while 40 occupying but a short interval of time, nevertheless affords a sufficient dwell at the end of the movement of the presser bars to tend to give a set to the deformed, distorted or warped wire and limit the reflex action thereof to a certain extent. 45 There will, however, be some reflexing of the material of the binder wire, and for this reason the crank 24 should be so set as to initially distort the wire beyond what is actually required in a completed book binding. 50

Rapid movement of the presser bars is desirable, since it overcomes the static inertia of the material of the binding wire or more readily overcomes the resistance to the movement of the presser bar. Ordinarily, the binder wire will have 55 from five to eight convolutions to the inch, and the aggregate resistance of such wire, when used in a book the bound edge of which is only four to six inches, would be considerable. By suddenly applying the distorting pressure to each 60 convolution, the resistance seems to be substantially reduced.

During the early stages of the movement of the presser bars, the spiral trend of the various leaves of the book is first corrected. This is followed by 65 the imparting of a slight reverse spiral trend to the leaves. With the return movement of the presser bars permitting a reflexure of the material of the binder wire, the reverse spiral trend is corrected, leaving all of the leaves in accurate 70 register with each other without any noticeable spiral trend to any of the leaves.

The fact that the operative portion of the presser bars 16 is adjacent the immovable rack bar 12 ensures the above mode of operation, since 75

the action of each presser bar is toward the top diameter of each convolution, and the lower portion of each convolution projecting beyond the edge of the back of the leaves is distorted as a result of the movement of the upper portion of the convolution by the presser bar.

With the descent of the upper rack bar 13, the roller 39 and its adjustable stem 38 follows the rack bar, the springs 35 maintaining the engagement between said roller and said bar. The rocking of the shaft 32 as a result of the descent of the roller 39 and the action of the springs 35 and 36 lowers the clamp bar 30 until the rack bar 13 passes out of engagement with the roller 39 so that the pressure exerted by the rack bar on all books being bound is limited by the tension of the springs 35 and 36. The clamp bar 30 engages the books before any substantial pressure has been applied to the various convolutions of the binder wire by the presser bars. The pressure exerted by the clamp bar 30 is sufficiently light to permit the shifting of the leaves of the book as the spiral trend of the binder wire is destroyed, and yet is sufficiently great to prevent any substantial movement of the book in its entirety during the later stages of the distortion of the binder wire. The clamp bar 30 will be engaged with the books, not only during the distorting movement of the presser bars 16, but during a part of the return of these bars to their normal position during the second 180° of movement of the crank 24.

Toward the completion of each cycle, the engagement of the rack bar 13 with the roller 39 and the resulting upward movement of said roller and its crank 37 imparts a reverse rotation to the shaft 32, disengaging the clamp bar 30 from the books and placing the springs 35 and 36 under tension preparatory to the next actuation of the machine.

I have described the use of a binder wire having five to eight convolutions to the inch. If this number be increased, it is obvious that the throw of the link 14 and of the various presser bars must be correspondingly lessened, and that if there are less than this number of convolutions to the inch, the throw of said parts must be increased. The crank 24 may be adjusted toward or from the axis of the wheel 23 so as to reduce or increase the throw of said parts, as required by variance in the pitch or in the number of convolutions of the binder wire to the inch.

In binding books of different thicknesses, the bearing member 38 for the roller 39 may be adjusted in relation to the crank arm 37 carrying same, to properly position said clamp bar to accommodate the desired thickness of the book, without varying the pressure exerted by the clamp bar.

In the accompanying drawing, I have shown presser bars 16 having a small lateral pitch. If desired, however, these bars may extend in a line truly perpendicular to the plane of the feed shelf, since the space between the bars is greater than the diameter of the binder wire.

If the diameter of the convolutions of a binder wire be greater than that for which the machine is set, the gauge plate 29 may be adjusted away from the presser bars, while if the diameter of said convolutions be smaller, said gauge plate may be adjusted toward said presser bars. Hence, by providing an adjustable gauge plate, the machine may be adapted for use with binder wires, the convolutions of which vary in diameter.

By providing for adjustability of the roller 39

in its relation to the rack bar 13, the machine may be accommodated to work upon books differing in thickness. By providing an adjustable crank pin 24, the machine may be adjusted to accommodate it to binder wires, the convolutions of which vary in pitch, or in which the number of convolutions per inch varies.

Whatever the setting of the machine in the respects noted above, the mode of operation, so far as the deforming, distorting or warping of the convolutions of the binder wire is concerned, is the same.

Notwithstanding that the machine is a high speed machine, the capacity of a machine may be increased by simultaneously feeding a number of books to the presser bars to be acted upon during each cycle of the machine. Notwithstanding the high speed at which the machine operates, there will be a gradual variation in the stresses applied to the various convolutions of the binder wire by the presser bars, due to the movement of the crank 24 from a horizontal center.

As heretofore stated, the initial movement of the bars is slow, followed by a rapid movement, which in turn is followed by a gradually slower movement until the presser bars come to rest. The reverse movement of the bars is in the same manner, thus holding the various convolutions in their deformed, distorted or warped shape for an interval sufficient to give sufficient set to the wire to limit its reflex action. In fact, the return movement of the presser bars will tend to impart a limited return movement to the convolutions so that as a result of the operation of the machine, substantially 180° of each convolution will occupy a plane at right angles to the axis of the binder wire, as shown in Fig. 5 of the drawing, and the pitch of the remaining 180° in arc of each convolution of the binder wire will have a higher degree of obliquity than in the original wire.

During the operation of the machine, the engagement of each convolution with the leaves of a book limits the action of the presser bars in a manner to secure the desired form in the completed binder wire, the clamp bar 30 being employed to aid in securing this effect by preventing movement of the book as a whole.

In the operation of a machine embodying the invention, it will be observed that notwithstanding the action of the clamp bar, the different leaves of a book may have a limited sliding movement in relation to each other, but there is no movement of the book as a whole.

It is not my intention to limit the invention to the details of construction and arrangement of parts shown in the accompanying drawing, it being obvious that such may be varied without departing from the spirit and scope of the invention.

Having described the invention, what I claim as new and desire to have protected by Letters Patent, is:—

1. A book binding machine embodying therein a feed shelf, a rack having a plurality of spaced presser bars positioned in a plane perpendicular to the plane of said feed shelf, actuating means for said rack whereby said presser bars are moved in relation to said feed shelf while engaging the convolutions of a binding wire of a book upon said feed shelf, to increase the obliquity of the portion of each such convolution projecting beyond the edge of the book, and means resisting movement of the book with said presser bars.

2. A book binding machine embodying therein a feed shelf, a rack having a fixed rack bar adjacent the feed shelf, a movable rack bar positioned above and spaced from said fixed rack bar, and a plurality of spaced presser bars extending between and pivotally connected with said rack bars, said presser bars being positioned in a plane perpendicular to the plane of said feed shelf, actuating means for said rack whereby said presser bars are moved in relation to said feed shelf while engaging the convolutions of a binding wire of a book upon said feed shelf, to increase the obliquity of the portion of each such convolution projecting beyond the edge of the book, and means resisting movement of the book with said presser bars.

3. A book binding machine embodying therein a feed shelf, a rack having a fixed rack bar adjacent the feed shelf, a movable rack bar positioned above and spaced from said fixed rack bar, and a plurality of spaced presser bars extending between and pivotally connected with said rack bars, said presser bars being positioned in a plane perpendicular to the plane of said feed shelf, links pivotally connected with the opposite ends of said rack bars respectively, a crank wheel having a crank, a pitman connecting said crank with one of said links whereby said presser bars are moved in relation to said feed shelf while engaging the convolutions of a binding wire of a book upon said feed shelf, to increase the obliquity of the portion of each such convolution projecting beyond the edge of the book, and means resisting movement of the book with said presser bars.

4. A book binding machine embodying therein a feed shelf, a rack having a fixed rack bar adjacent the feed shelf, a movable rack bar positioned above and spaced from said fixed rack bar, and a plurality of spaced presser bars extending between and pivotally connected with said rack bars, said presser bars being positioned in a plane perpendicular to the plane of said feed shelf, links pivotally connected with the opposite ends of said rack bars respectively, a crank wheel having a crank, a pitman connecting said crank with one of said links whereby said presser bars are moved in relation to said feed shelf while engaging the convolutions of a binding wire of a book upon said feed shelf, to increase the obliquity of the portion of each such convolution projecting beyond the edge of the book, means whereby said crank may be adjusted radially of its wheel to vary the throw of said presser bars, and means resisting movement of the book with said presser bars.

5. A book binding machine embodying therein a feed shelf, a rack having a fixed rack bar adjacent the feed shelf, a movable rack bar positioned above and spaced from said fixed rack bar, each of said rack bars having a sequence of spaced bearing sockets therein, a plurality of presser bars having ends turned at substantially right angles to the portion of the presser bars between said rack bars, said turned ends entering the bearing sockets in said rack bars, and cap plates carried by said rack bars holding said presser bars in engagement therewith, said presser bars being positioned in a plane perpendicular to the plane of said feed shelf, actuating means for said rack whereby said presser bars are moved in relation to said feed shelf while engaging the convolutions of a binding wire of a book upon said feed shelf, to increase the obliquity of the portion of each such convolution projecting be-

yond the edge of the book, and means resisting movement of the book with said presser bars.

6. A book binding machine embodying therein a feed shelf, a rack having a fixed rack bar adjacent the feed shelf, a movable rack bar positioned above and spaced from said fixed rack bar, each of said rack bars having a sequence of spaced bearing sockets therein, a plurality of presser bars having ends turned at substantially right angles to the portion of the presser bars between said rack bars, said turned ends entering the bearing sockets in said rack bars, and cap plates carried by said rack bars holding said presser bars in engagement therewith, said presser bars being positioned in a plane perpendicular to the plane of said feed shelf, links pivotally connected with the opposite ends of said rack bars respectively, a crank wheel having a crank, a pitman connecting said crank with one of said links whereby said presser bars are moved in relation to said feed shelf while engaging the convolutions of a binding wire of a book upon said feed shelf, to increase the obliquity of the portion of each such convolution projecting beyond the edge of the book, and means resisting movement of the book with said presser bars.

7. A book binding machine embodying therein a feed shelf, a rack having a plurality of spaced presser bars positioned in a plane perpendicular to the plane of said feed shelf, actuating means for said rack whereby said presser bars are moved in relation to said feed shelf while engaging the convolutions of a binding wire of a book upon said feed shelf, to increase the obliquity of the portion of each such convolution projecting beyond the edge of the book, a clamp bar positioned above said feed shelf, and means for engaging said clamp bar with a book upon said shelf substantially simultaneously with the movement of said presser bars.

8. A book binding machine embodying therein a feed shelf, a rack having a plurality of spaced presser bars positioned in a plane perpendicular to the plane of said feed shelf, actuating means for said rack whereby said presser bars are moved in relation to said feed shelf while engaging the convolutions of a binding wire of a book upon said feed shelf, to increase the obliquity of the portion of each such convolution projecting beyond the edge of the book, a clamp bar positioned above said feed shelf, a spring operative upon said clamp bar for developing a yielding pressure upon books upon the feed shelf, and means controlled by said rack whereby said clamp bar is actuated by said springs simultaneously with the movement of the presser bars.

9. A book binding machine embodying therein a feed shelf, a rack having a plurality of spaced presser bars positioned in a plane perpendicular to the plane of said feed shelf, actuating means for said rack whereby said presser bars are moved in relation to said feed shelf while engaging the convolutions of a binding wire of a book upon said feed shelf, to increase the obliquity of the portion of each such convolution projecting beyond the edge of the book, a crank shaft having a plurality of cranks, an arm rigidly secured to a crank upon said shaft, a clamp bar carried by said arm and positioned above said feed shelf, a torsion spring acting upon said shaft, a bearing member carried by another crank upon said shaft, and a roller carried by said bearing member and engaging said rack, whereby said clamp

bar is actuated by said springs simultaneously with the movement of the presser bars.

10. A book binding machine embodying therein a feed shelf, a rack having a plurality of spaced presser bars positioned in a plane perpendicular to the plane of said feed shelf, actuating means for said rack whereby said presser bars are moved in relation to said feed shelf while engaging the convolutions of a binding wire of a book upon 10 said feed shelf, to increase the obliquity of the portion of each such convolution projecting beyond the edge of the book, a crank shaft having a plurality of cranks, an arm rigidly secured to a crank upon said shaft, a clamp bar carried by 15 said arm and positioned above said feed shelf, a torsion spring acting upon said shaft, a bearing member adjustably connected with another crank upon said shaft, and a roller carried by said bearing member and engaging said rack, whereby 20 said clamp bar is actuated by said springs simultaneously with the movement of the presser bars.

11. A book binding machine embodying therein a feed shelf, a rack having a plurality of spaced presser bars positioned in a plane perpendicular to the plane of said feed shelf, actuating means for said rack whereby said presser bars are moved in relation to said feed shelf while engaging the convolutions of a binding wire of a book upon 25 said feed shelf, to increase the obliquity of the portion of each such convolution projecting beyond the edge of the book, a gauge plate carried by said feed shelf and spaced from said presser bars, and means resisting movement of the book 30 with said presser bars.

12. A book binding machine embodying therein a feed shelf, a rack having a plurality of spaced presser bars positioned in a plane perpendicular to the plane of said feed shelf, actuating means for said rack whereby said presser bars are moved in relation to said feed shelf while engaging the convolutions of a binding wire of a book upon 40 said feed shelf, to increase the obliquity of the portion of each such convolution projecting beyond the edge of the book, a gauge plate carried by said feed shelf and spaced from said presser bars, means whereby said gauge plate may be 45 adjusted toward and from said presser bars, and means resisting movement of the book with said presser bars.

13. A book binding machine embodying therein a feed shelf, a rack having a fixed rack bar adjacent the feed shelf, a movable rack bar positioned above and spaced from said fixed rack bar, and a plurality of spaced presser bars extending between and pivotally connected with said rack bars, said presser bars being positioned in a plane perpendicular to the plane of said feed shelf, actuating means for said rack whereby 55 said presser bars are moved in relation to said feed shelf while engaging the convolutions of a binding wire of a book upon said feed shelf, to increase the obliquity of the portion of each such convolution projecting beyond the edge of the book, a clamp bar positioned above said feed shelf, and means for engaging said clamp bar 60

with a book upon said shelf substantially simultaneously with the movement of said presser bars.

14. A book binding machine embodying therein a feed shelf, a rack having a fixed rack bar adjacent the feed shelf, a movable rack bar positioned above and spaced from said fixed rack bar, and a plurality of spaced presser bars extending between and pivotally connected with said rack bars, said presser bars being positioned in a plane 10 perpendicular to the plane of said feed shelf, actuating means for said rack whereby said presser bars are moved in relation to said feed shelf while engaging the convolutions of a binding wire of a book upon said feed shelf, to increase the 15 obliquity of the portion of each such convolution projecting beyond the edge of the book, a gauge plate carried by said feed shelf and spaced from said presser bars, and means resisting movement of the book with said presser bars. 20

15. A book binding machine embodying therein a feed shelf, a rack having a fixed rack bar adjacent the feed shelf, a movable rack bar positioned above and spaced from said fixed rack bar, and a plurality of spaced presser bars extending between and pivotally connected with said rack bars, said presser bars being positioned in a plane perpendicular to the plane of said feed shelf, links pivotally connected with the opposite ends of said rack bars respectively, a crank 25 wheel having a crank, a pitman connecting said crank with one of said links whereby said presser bars are moved in relation to said feed shelf while engaging the convolutions of a binding wire of a book upon said feed shelf, to increase the 30 obliquity of the portion of each such convolution projecting beyond the edge of the book, means whereby said crank may be adjusted radially of its wheel to vary the throw of said presser bars, a gauge plate carried by said feed shelf and 35 spaced from said presser bars, means whereby said gauge plate may be adjusted toward and from said presser bars, and means resisting movement of the book with said presser bars.

16. A book binding machine embodying therein a feed shelf, a rack having a fixed rack bar adjacent the feed shelf, a movable rack bar positioned above and spaced from said fixed rack bar, and a plurality of spaced presser bars extending between and pivotally connected with 45 said rack bars, said presser bars being positioned in a plane perpendicular to the plane of said feed shelf, links pivotally connected with the opposite ends of said rack bars respectively, a crank wheel having a crank, a pitman connecting said 50 crank with one of said links whereby said presser bars are moved in relation to said feed shelf while engaging the convolutions of a binding wire of a book upon said feed shelf, to increase the 55 obliquity of the portion of each such convolution projecting beyond the edge of the book, a manually operative clutch mechanism whereby said source of power may be connected with said crank wheel, and means resisting movement of the book with said presser bars. 60
